CLOTHESLINE REEL

Ralph J. Kingsley, Buffalo, N. Y.

Application June 21, 1951, Serial No. 232,795

2 Claims. (Cl. 242—101)

1

This invention relates to improvements in clothesline reels upon which one or more clotheslines may be wound when not in use, and from which the clothesline or lines may be readily unwound for use.

One of the objects of this invention is to provide a clothesline reel of improved and simplified construction which is of strong and reliable construction and easily manipulated. Another object is to provide a device of this type with a ratchet mechanism of improved construction for preventing unwinding of the clothesline or lines when the same are in position to support clothes or other articles, and which can be readily released to permit unwinding of the clothesline.

Other objects and advantages will be apparent from the following description of one embodiment of the invention and the novel features will be particularly pointed out hereinafter in connection with the appended claims.

In the accompanying drawings:

Fig. 1 is an end elevation of a clothesline reel embodying this invention showing the clothesline in position for use.

Fig. 2 is a sectional plan view thereof, on line 2—2 of Fig. 1.

Fig. 3 is a transverse sectional elevation thereof, on line 3—3 of Fig. 2, on an enlarged scale.

Fig. 4 is a fragmentary section thereof, on line 4—4, Fig. 3, on a still larger scale.

Fig. 5 is a transverse sectional elevation thereof, on line 5—5, Fig. 2.

The clothesline reel is preferably mounted on a suitable base 1 which may be of wood or other material, and on which the parts of the clothesline reel are mounted. The base may be secured to a wall 8 or other suitable support.

The reel includes a winding drum 9 mounted for rotation relatively to the base 1. Any suitable means may be employed for rotatably mounting the winding drum 9 on the base, and in the construction shown for this purpose, a supporting member 10 is provided, one end of which has a flange which is suitably secured to the base 1, and which has a wall or web extending outwardly from the base and provided with an aperture into which a pintle or axle 11 of the drum may extend. The other end of the drum is supported as hereinafter fully described in another supporting member of U-shaped form having the intermediate portion thereof secured to the base and having an outwardly extending plate or wall 14 arranged adjacent to the other end of the drum 9 and another outwardly extending plate or web 15 extending substantially parallel to the plate or web 14 and spaced therefrom.

2

The drum 9 may be rotatably mounted on the plates or webs 14 and 15 by means of a winding shaft 16 extending through aligned apertures in the webs 14 and 15, and having a crank wheel 17 secured to the outer end thereof. This wheel has a crank 18 by means of which the shaft 16 may be easily rotated.

The shaft 16 may be connected with the winding drum 9 in any suitable manner so as to hold the end of the drum adjacent to the shaft in correct relation for rotation and to permit lengthwise movement of the shaft 16 relatively to the drum 9. Any suitable splined or driving connection may be employed for this purpose, and in the construction shown, the end of the reel adjacent to the shaft 16 is provided with a diametrically extending slot 20 and an axially extending aperture 21 into which the shaft 16 extends. In order to form a driving connection between the shaft 16 and the adjacent end of the drum 9, the shaft is provided at the inner end thereof with a transversely extending plate or key 24 rigidly secured thereto, which is formed to fit into the slot 20 of the end of the winding drum. By means of this construction, it will be readily seen that the shaft 16 when revolved by means of the crank 18 will transmit rotary motion to the winding drum by means of the plate or key 24 and the shaft 16 may be moved lengthwise of the winding drum to a limited extent. During rotation of the winding drum, the same will be held in concentric relation to the shaft 16 by means of the aperture 21 in the shaft.

25 represents a series of clotheslines, one end of each of which may be secured to the drum. The other ends of the clotheslines 25 are preferably secured to a rod or bar 26 which may be readily attached to a wall or other support 27, for example, by means of hooks 28 which may be secured to a plate 29 which in turn is secured to the wall or support 27, if the clotheslines are to be strung between two walls of a room. The bar 26 may readily be disengaged from the hooks 28 and permitted to move toward the reel so that the clotheslines may be wound on the winding drum 9. Any other means may be provided for supporting the outer ends of the clotheslines. While I have shown my reel as applied for use in connection with a number of clotheslines, yet it will be understood that the improvements herein described may equally well be used with a reel for supporting only a single clothesline.

In order to prevent further unwinding of the clotheslines 25 from the winding drum after the desired length of clotheslines has been unwound therefrom, I provide a ratchet mechanism which

3

will hold the drum 9 against turning in a direction to unwind the clotheslines 25 therefrom. In the construction shown, I have provided the supporting plate or web 15, which also forms an end wall of the housing of the clothesline reel, with a plurality of ratchet teeth. This may, for example, be done by providing on the wall or plate 15 a series of cuts 32 arranged in a circle concentric with the shaft 16, and then forcing the metal adjacent to one side of each of the cuts outwardly as shown at 33, see particularly Fig. 4. In this manner, there will be formed a series of projections having sloping or inclined sides terminating at the cuts 32 in abrupt edges. The end wall or web 15, consequently, constitutes a ratchet and this ratchet cooperates with a latch member 35 of any desired shape or form secured to the winding shaft 16. In the particular construction shown, this ratchet member is in the form of a rectangular plate or bar having a hub portion 36 which may be suitably secured to a winding shaft 16. It will, consequently, be seen that when the latch member is moved into its operative position in close proximity to the plate or wall 15, the edges of this latch member will engage with the abrupt faces of the ratchet teeth 33, and thus prevent rotation of the winding shaft in one direction. If the winding shaft is turned in the opposite direction, the latch member will readily ride over the inclined faces 33 of the ratchet teeth, which faces will not interfere with the turning of the shaft 16 in such direction.

Means are provided for normally urging the latch member 35 into engagement with the teeth of the ratchet, and in the construction shown for this purpose, a yielding member, such as a coil spring 38 extends about the shaft 16. This spring at one end thereof bears against the supporting member or plate 14 and, if desired, a washer may be interposed between this spring and the plate. The other end of the spring engages the hub portion 36 of the latch member, thus urging the latch member 35 into engagement with the ratchet member or end wall 15. However, since the shaft 16 is movable lengthwise of the winding drum 9, it will be obvious that if pressure is applied to the outer face of the wheel or disk 17, the latch member 35 will move against the action of the spring 38 out of engagement with the teeth of the ratchet member, whereupon the drum may be turned in a direction to permit unwinding of the clothesline therefrom.

In the use of the clothesline reel described, when it is desired to unwind the clotheslines from the winding drum, it is merely necessary to apply pressure to the outer face of the wheel or disk 17 to move the latch member 35 out of engagement with the ratchet teeth. The clotheslines can then be unwound from the winding drum by merely pulling the same outwardly to the desired extent. After the outer ends of the clotheslines have been secured to a support, for example, when the bar 26 has been secured to the hooks 28, the crank 18 may be turned in a direction to wind the clotheslines on the drum 9, during which rotation the latch member 35 will ride over the inclined faces of the ratchet teeth 33. This may be done without pushing the wheel or disk 17 and the shaft inwardly toward the winding drum, in which case the latch member 35 will ride over the ratchet teeth. When the clotheslines have been tightened to the desired extent, the ratchet mechanism will prevent unwinding of the clotheslines from the winding drum. If desired, the shaft may be turned in the direction for winding

the clotheslines on the drum while pushing the crank 18 toward the drum, in which case, the latch member will rotate without contacting the ratchet teeth. When the clotheslines have been wound on the drum to the desired extent, the crank 18 is released, whereupon the spring 38 will move the latch into engagement with the ratchet teeth, thus preventing unwinding of the lines from the drum. Consequently, when the desired tension has been applied to the clothes-lines, they will be maintained in this position by means of the ratchet mechanism.

means of the ratchet mechanism.

40 represents a cover of sheet metal or other suitable material which may be secured to the base or to the outwardly extending supporting members 10, 14 and 15, in any suitable or desired manner. In the construction shown, the cover member is provided with flanges 41, Fig. 3, which may be secured by screws or other means to the base 7. The cover member is provided with suitable holes or apertures 42 through which the clotheslines may pass. When the clotheslines are not needed, the winding drum may be rotated by means of the crank 18 to wind the clotheslines on the winding drum, whereupon the bar 26 will lie against the outer surface of the cover member 40 of the reel.

It will be understood that various changes in the details, materials, and arrangements of parts which have been herein described and illustrated in order to explain the nature of the invention, may be made by those skilled in the art within the principle and scope of the invention, as expressed in the appended claims.

35 I claim as my invention:

I claim as my invention:

1. In a clothesline reel including a winding drum on which a clothesline may be wound and a base, that improvement which includes a supporting member secured to said base and extending outwardly therefrom in position to rotatably support one end of said drum, a pair of supporting members secured to said base and extending outwardly therefrom in spaced relation to the other end of said drum and spaced apart lengthwise of each other, a shaft rotatably mounted in said last mentioned supporting members, said drum having an axial bore in the end thereof adjacent to said shaft into which said shaft may extend, said drum also having a diametrical slot in said last mentioned end of said drum intersecting said bore, a plate secured to said shaft and extending radially with reference to the same and slidably lengthwise of said slot in said drum and forming a driving connection between said shaft and said drum, a ratchet mechanism including a stationary ratchet member, a latch secured to said shaft and movable into and out of engagement with said ratchet by movement of said shaft relatively to said drum, said ratchet member having teeth with which said latch cooperates to hold said shaft and drum from rotating in a direction to unwind said clothesline from said drum, a spring normally holding said latch in engagement with said ratchet, said latch being movable out of engagement with said ratchet when said shaft is moved toward said drum, to permit rotation of said drum for unwinding of a clothesline therefrom.

70   2. In a clothesline reel having a winding drum on which a clothesline may be wound and a base, that improvement which includes a supporting member secured to said base and extending outwardly therefrom in position to rotatably support one end of said drum, another supporting member of U-shaped form having its intermedi-

ate portion secured to said base and having legs spaced apart and extending outwardly from said base, a shaft rotatably mounted on said legs and movable in the direction of its length to a limited extent, a splined connection between said shaft and said drum which permits said shaft to move endwise relatively to said drum, one of said legs having ratchet teeth extending outwardly therefrom toward the other leg, a latch member secured on said shaft and formed to engage with 10 said ratchet teeth, and a spring interposed between one of said legs and said latch and yieldingly urging said latch into engagement with said ratchet teeth, said ratchet teeth cooperating with said latch to enable said shaft to rotate said drum in a direction for winding said clothesline thereon and resisting rotation in the

other direction, said shaft when moved toward said drum disengaging said latch from said teeth to permit unwinding of said clothesline from said drum.
